ELECTRIC SWITCH

Felix J. Watts, Bronson, Mich., assignor to Harry
A. Douglas, Bronson, Mich.

Application July 13, 1932. Serial No. 622,225

5 Claims. (Cl. 200—6)

This invention relates to electric switches, and, among other objects, aims to provide an improved switch in controlling relation with two electric circuits, one of said circuits being always closed.

- 5 The invention is desirably inclusive of means for actuating the switch to one of its alternative operative positions combined with spring means for returning the switch to the other operative position when said actuating means are released. 10 The invention is of particular utility in connection with electrically energized gauges such as are employed on motor vehicles to indicate the oil pressure or the quantity of fuel.

My invention will be understood by reference 15 to the illustrative embodiment shown in the accompanying drawing, in which—

Figure 1 is a longitudinal section through a switch embodying my invention;

Figure 2 is a left-hand end view of the structure of Figure 1;

Figure 3 is a section taken on the line 3—3 of Figure 1;

Figure 4 is a section taken on the line 4—4 of Figure 1 looking in the opposite direction from the section of Figure 3; and

Figure 5 is a side elevation of the structure of Figure 1 showing illustrative circuits associated therewith.

In the illustrative construction the metallic 30 casing 1 is cylindrical and is closed at one end by a bushing 2 which is exteriorly threaded as at 3. A switch may be mounted for example on the instrument panel 4 of an automotive vehicle by having the bushing 2 pass through a suitable 35 aperture in the mounting and a clamping nut 5 screwed on the threads 3.

At its other end the casing 1 carries an insulating block 6 which also forms a closure for this end of the casing, ears 7 being formed on the 40 casing and received in notches 8 in the periphery of the insulating block and thereafter bent over the block. At its side opposite the notches 8, the block 6 is continued laterally beyond the casing 1 and at this side of the block, ears 9 formed on 45 the casing, extend through slots 10 in the block and are thereafter bent over the block.

The insulating block 6 carries, in this instance, three parallel insulated contacts 11, 12 and 13, the contacts 11 and 12 being inside the casing 50 and the third contact 13 being outside the casing disposed upon the laterally extended portion 14 of the block 6.

Each of the contacts 11, 12 and 13 has integral therewith wire binding means such as the wire 55 terminal receiving sleeves 15, 16 and 17, respec-

tively, having associated therewith the usual spring pressed detents 18 for snapping over the wire terminals (not shown).

Fixedly secured to the contact 13 and mechanically and electrically connected therewith as by being clamped between the sleeve 17 and the block 6 I have shown a contact bar 19 having two branches 20 which are carried by the block 6 spaced from the other contacts. The bar branches 20 each has an angular portion 21 which passes through the block 6 into the interior of the casing 1 between the contacts 11 and 12 that are within the casing, but offset one on each side of these contacts. One of these contacts within the casing, in this instance the contact 11, and the angular portions 21 of the contact bar 19 are continued longitudinally within the casing beyond the other contact which is within the casing, in this instance the contact 12, for a purpose presently pointed out. The contact 11 is longitudinally continued as at 22.

Fixedly secured to the contact 12, I have shown a resilient metallic mounting 23 having at one end an angular portion 24 through an aperture 25 in which the contact 12 passes, thereby clamping 80 the mounting 23 to the block 6 and electrically connecting said mounting with the contact 12. To prevent rotation of the mounting 23 with respect to the block 6, the portion 24 has an angularly directed tail 26 which is received in a slot 85 27 in the block 6.

At its other end the mounting 23 has another angularly related portion 28 provided at each side with ears 29. The portion 28 constitutes a fulcrum for the circuit controlling arm 30 which is here shown hinged intermediate its ends on said fulcrum, as by having the ears 29 received in notches 31 in the sides of the arm 30 and thereafter bent over the arm. At one end 32 the arm 30 is bent to be transverse to the contacts 11, 12 and 13 and to the portions 21 of the contact bar 19. At this end 32 of the arm 30 the arm passes between the portions 21 of the contact bar 19 and terminates in an edge 32a engageable with the portion 22 of the contact 11. To engage the bar 19, the arm 30 has its edge 32a laterally extended in fingers 33 which are disposed between the portions 21 of the contact bar 19 and the continuation 22 of the contact 11. The arm 30 thus constitutes a contact movable, as presently described, to cause either its edge 32a to engage the portion 22 of the contact 11, or, its fingers 33 to engage the portions 21 of the contact bar 19. To effect movement of the arm 30 on its fulcrum, I have shown an insulating actuator 34 suitably 110

carried by one end of the reciprocal actuator rod 35 which passes through and is slidable in the bushing 2. Upon the side of the mounting 4 opposite to the casing 1, the actuator rod 35 5 may terminate in a head 36 which is separated from the main body of the rod by an annular recess 37. A handle 38 has its hollow shank 39 passed over the head 36 and spun into the recess 37 to secure the handle to the rod. Movement 10 of the rod 35 in one direction may be limited by abutment of the shank 39 with the bushing 2.

The actuator 34 is shown in the form of a plate having one edge 40 shaped to conform to the curvature of the casing 1 and in close contact with the wall of the casing, this edge being notched as at 41 to receive slidable therein a longitudinal rib 42 pressed inwardly of the casing. This engagement of the actuator and casing prevents rotation of the actuator with respect to the casing, 20 but permits relative longitudinal movement of these parts. The opposite edge 43 of the actuator rides upon the arm 30 between the ears 29 of its fulcrum 28 and presses the arm either into engagement with the portion 22 of the contact 11 or the portions 21 of the contact bar 19. The arm 30 is thus a movable contact in permanent electrical engagement with the contact 12 and complementary alternately with either the contact 11 or the contact 13. When the actuator 34 is in the 30 position shown in full lines in Figure 1, the arm 30 has its fingers 33 pressed into engagement with the portions 21 of the contact bar 19 and a circuit is completed from the grounded battery 44 through wire 44a, sleeve 16, contact 12, arm 30, 35 contact bar 19, contact 13, sleeve 17, wire 45 and through the grounded gauge 46 which may be the gauge indicating the quantity of fuel carried by the motor vehicle at any given time. When the handle 38 is pulled upon to reciprocate the actuator 40 over the fulcrum 28 to press upon the arm 30 upon the opposite side of its fulcrum, as indicated in dotted lines in Figure 1, the edge 32a of the arm 30 is pressed into engagement with the portion 22 of the contact 11. The earlier described 45 circuit is thereupon broken and another circuit is established through the grounded battery 44, wire 44a, sleeve 16, contact 12, arm 30, contact 11, sleeve 15, wire 47 and through the grounded gauge 48 which may indicate the oil 50 pressure, for example, of the lubricating system. The actuator 34 is permitted to pass by the fulcrum 28, while still pressing upon the arm 30, by the resiliency of the mounting 23 which yields sufficiently for this purpose. The structure of 55 this circuit controlling arm is broadly claimed in my copending application, Serial No. 473,823, filed August 8, 1930.

In accordance with my invention, I have arranged means for returning the actuator to one of its alternative positions when the handle 38 is released, such as the position shown in full lines in Figure 1 in which the gauge 46 is normally energized, as described. Such means is here represented by the compression coil spring 49 surrounding the rod 35 and pressing at one end upon the bushing 2 and upon its other end upon the actuator 34, thus urging the actuator to its innermost position in which the arm 30 is placed in electrical contact with the contact bar 19. The bushing 2 may be advantageously recessed axially as at 50 to receive the spring 49. Such recessing also facilitates the production of a flange 51 on the bushing by which the bushing is clamped to the casing 1.

Having described an embodiment of my invention, I claim:

1. In an electric switch, the combination of three parallel insulated contacts, two of said contacts being continued longitudinally beyond the third; a metallic mounting fixedly engaging the contact which is not continued; a circuit controlling arm fulcrumed intermediate its ends on said mounting, one end of said arm being bent to be transverse to the contact and terminating in an edge disposed between the contacts that are continued longitudinally, said arm being movable to engage said edge alternatively with one or the other of said continued contacts; and a reciprocal actuator pressing upon the arm alternatively upon either side of its fulcrum to press the edge into engagement with one or the other of said continued contacts in alternative positions of the actuator. 80 85 90

2. In an electric switch, the combination of three parallel insulated contacts, two of said contacts being continued longitudinally beyond the other; a metallic mounting fixedly engaging said contact which is not continued; a circuit controlling arm fulcrumed intermediate its ends on said mounting, one end of said arm being bent to be transverse to the contacts and terminating in an edge disposed between the contacts that are continued longitudinally, said arm being movable to engage said edge alternatively with one or the other of said continued contacts; a reciprocal actuator pressing upon the arm alternatively upon either side of its fulcrum to press the edge into engagement with one or the other of said continued contacts in alternative positions of the actuator; and a spring urging the actuator into one of said alternative positions. 95 100 105 110 115

3. In an electric switch, the combination of three parallel insulated contacts, two of said contacts being continued longitudinally beyond the other; a resilient metallic mounting fixedly engaging said contact which is not continued; a circuit controlling arm fulcrumed intermediate its ends on said mounting, one end of said arm being bent to be transverse to the contacts and terminating in an edge disposed between the contacts that are continued longitudinally, said arm being movable to engage said edge alternatively with one or the other of said continued contacts; a reciprocal actuator pressing upon the arm alternatively upon either side of its fulcrum to press the edge into engagement with one or the other of said continued contacts in alternative positions of the actuator; and a spring urging the actuator into one of said alternative positions. 120 125 130 135

4. In an electric switch, the combination with a metallic casing; of an insulating block carried by and forming a closure for said casing; parallel insulated contacts carried by said block, two of said contacts being inside the casing and the third disposed upon a laterally extended portion of the block outside the casing; wire terminal receiving means integral with said contacts upon the outside of the casing; a contact bar fixedly secured to the contact outside the casing and carried by the insulating block spaced from the other contacts, said bar having an angular portion passing through the insulating block into the interior of casing between the contacts that are within the casing, said angular portion and one of said contacts within the casing being continued longitudinally beyond the other contact which is within the casing; a me- 140 145 150

metallic mounting fixedly engaging said contact that is not continued; a circuit controlling arm fulcrumed intermediate its ends on said mounting, one end of said arm being bent to be transverse to the contacts and terminating in a contact edge disposed between the contact bar and the contact that is continued longitudinally, said arm being movable to engage said edge alternately with one or the other of the bar or continued contact; and a reciprocable actuator pressing upon the arm alternately upon either side of its fulcrum to press the finger into engagement with one or the other of said bar or continued contact in alternative positions of the actuator.

5 5. In an electric switch, the combination with a metallic casing; of an insulating block carried by and forming a closure for said casing; parallel insulated contacts carried by said block, two of said contacts being inside the casing and the third disposed upon a laterally extended portion of the block outside the casing; wire terminal receiving means integral with said contacts upon the outside of the casing; a contact bar fixedly secured to the contact outside the casing and carried by the insulating block spaced from the

10 other contacts, said bar having an angular portion passing through the insulating block into the interior of casing between the contacts that are within the casing, said angular portion and one of said contacts within the casing being continued longitudinally beyond the other contact which is within the casing; a metallic mounting fixedly engaging said contact that is not continued; a circuit controlling arm fulcrumed intermediate its ends on said mounting, one end of said arm being bent to be transverse to the contacts and terminating in a contact edge having laterally directed finger extensions and disposed between the contact bar and the contact that is continued longitudinally, said arm being movable to engage said edge alternately with one or the other of the bar or continued contact; a reciprocable actuator pressing upon the arm alternately upon either side of its fulcrum to press the edge into engagement with one or the other of said bar or continued contact in alternative positions of the actuator; and a spring urging the actuator into one of said alternative positions.
